ASH HANDLING EQUIPMENT

Filed Jan. 10, 1927

INVENTOR
Oliver S. Bowman

UNITED STATES PATENT OFFICE.

OLIVER S. BOWMAN, OF COLORADO SPRINGS, COLORADO.

ASH-HANDLING EQUIPMENT.

Application filed January 10, 1927. Serial No. 160,241.

My invention relates to improved ash handling equipment, and the objects of my improvement are, first, to provide means for utilizing the chimney draft to eliminate dust and fumes incident to ash removal; second, to provide an ash container, with means for depositing ashes in ash pit or the like without dust; and third, to afford means for the escape via the chimney of gases arising from any partially consumed fuel in the ash.

I attain these objects by the mechanism illustrated in the accompanying drawings, in which—

15 Figure 1 is a vertical section on line A A in Fig. 3, showing the container and the hood separable; Fig. 2, a plan view of the type of hood shown in Fig. 1; Fig. 3, a vertical elevation, partly in section, of the hood shown in Fig. 1; Fig. 4, a vertical elevation, partly in section, of an alternative construction in which the hood is fixed to the container; Fig. 5, a plan view of Fig. 6; Fig. 6, a vertical section on line B B in Fig. 4; 25 Fig. 7, a fragmentary sectional elevation on line C C in Fig. 2.

Although I show the preferred embodiment of my invention, I do not thereby limit myself to the precise form shown, but wish myself to understand that various changes in the details of construction may be made within the scope of the claims.

Like numerals refer to like parts throughout the drawing.

35 The container A comprises cylindrical shell 1 having slot 6 in its lower edge to which is fixed bottom 2 having opening 3 therein, annular conical shell 4 disposed within shell 1 with its smaller opening concentric with opening 3 and its lower edge in close proximity to bottom 2, a slidable plate 5 disposed on said bottom and extending through said slot; and handles 7 and 23.

For the type of equipment wherein container and hood are separable hood B comprises plane circular sheet 8 having depending rim 9 and a rectangular opening over which is fixed rectangular shell 10 having an open end in which plate 11, containing slot 12, is vertically hung from hinge 11^a, so as to permit its being swung inward or outward as indicated by dotted outlines

in Fig. 7; a pan 13 fixed to sheet 8, and handles 14.

Thimble 15 is mounted on shell 10 and is 55 in open communication with interior of hood B; pipe 18, having angular slots 19, in which thimble 15 is movably mounted, is in open communication with chimney flue, via smoke pipe 20; damper 16, mounted on shaft 60 17, the ends of which project through slots 19, is disposed in thimble 15.

For the type of equipment wherein container and hood are not separable, the hood C comprises plane circular sheet 8^a fixed at 65 its outer edge to container shell 1^a, and having a rectangular opening over which is fixed rectangular shell 10^a having an open end over which plate 11^b, provided with handle 24, is hung from hinge 11^c, so as to permit 70 its being swung outward and upward as indicated by dotted outline in Fig. 6.

Thimble 21, fixed on upper face of shell 10^a, is in open communication with interior of hood C; pipe 18^a is fixed to and is in 75 open communication with smoke pipe 20; damper 16^a, mounted on shaft 17^a is disposed within pipe 18^a; sleeve 15^a, provided with handles 22 and angular slots 19^a, is slidably mounted on pipe 18^a and detachably 80 connected with thimble 21.

In operation, damper 16 is opened and ashes then shoveled into container A through opening in hood B. Plate 11, pushed inward as the shovel enters, returns 85 to a vertical position with the shovel handle in slot 12, and as the shovel is withdrawn swings outward. Dust and gas from the ashes escape into the chimney via thimble 15 and pipes 18 and 20. As damper 16, which 90 is then shut, does not entirely close pipe 15, gases from partially consumed fuel in the ash escape via thimble 15 and pipes 18 and 20 into the chimney.

Pan 13 is designed to catch any ash 95 dropped from shovel.

When container is filled hood B is lifted and turned until the projections of damper shaft 17 enter the horizontal sections of angular slots 19. Container may then be removed, placed over an ash pit or the like, plate 5 withdrawn by means of handle 23, and the ash precipitated into pit.

With the alternative construction shown,

wherein the hood and container are integral, the operation differs from the above in that cover 11^b is opened to position indicated by dotted outline in Fig. 6, the ashes shoveled 5 into the container and cover 11^b closed. When container is filled, sleeve 15^a is lifted and turned until the horizontal sections of angular slots 19^a are entered by the projections of damper shaft 17^a, thus detaching 10 container.

When the containers are being emptied, an ordinary lid may be used to cover the open end to prevent the escape of ash dust.

I claim:

- 15 1. In an equipment of the class described, the combination of a container, comprising a cylindrical shell having a slot in its lower edge, a bottom having an opening therein, and an inverted conical shell disposed within 20 said cylindrical shell in proximity to said bottom; a slidable plate disposed on said bottom and extending through said slot; a hood, comprising a plane circular sheet having a depending rim and a rectangular opening, a rectangular shell open below and at its 25 front end, fixed to said circular sheet above said rectangular opening; a plate, having a slot therein, hinged to the front top edge of said rectangular shell; a pan fixed to 30 said circular sheet in proximity to said open end; a thimble mounted on said rectangular shell and in open communication therewith; a damper, mounted on an operating shaft, disposed within said thimble; and a pipe, having a pair of angular slots through which the ends of said operating shaft project, mounted loosely on 35 said thimble and adapted to be connected with a smoke pipe or a chimney.
- 40 2. In an equipment of the class described, the combination of a container comprising a shell having a slot in its lower edge, a bottom having an opening therein and an inwardly tapering shell disposed within said 45 shell in proximity to said bottom; a slidable plate disposed on said bottom and extending through said slot; a hood, comprising a sheet having an opening therein, and a shell open below and at one end, fixed to said 50 sheet above said opening; a plate, having a slot therein, hinged to the top edge of open end of said shell; a pan fixed to said sheet in proximity to said open end; a thimble, mounted on said shell and in open 55 communication therewith; a damper, mounted on an operating shaft, disposed within said thimble; and a pipe, having a pair of angular slots through which the ends of said operating shaft project, mounted loosely on 60 said thimble and adapted to be connected with a smoke pipe or a chimney.
- 65 3. In an equipment of the class described, the combination of a container; a hood, comprising a sheet having an opening therein, and a shell open below and at one end, fixed

to said sheet above said opening; a plate, having a slot therein, hinged to the top edge of open end of said shell; a pan fixed to said sheet in proximity to said open end; a thimble, mounted on said shell and in open communication therewith; a damper, mounted on an operating shaft, disposed within said thimble; and a pipe, having a pair of angular slots through which the ends of said operating shaft project, mounted loosely on 70 said thimble and adapted to be connected with a smoke pipe or a chimney.

4. In an equipment of the class described, the combination of a container, comprising a cylindrical shell having a slot in its lower edge, a bottom having an opening therein, and an inverted conical shell disposed within 80 said cylindrical shell in proximity to said bottom; a slidable plate disposed on said bottom and extending through said slot; a hood, comprising a plane circular sheet fixed to top of said container, having a rectangular opening therein, and a rectangular shell, open below and at its front end, fixed to 85 said circular sheet above said rectangular opening; a pan fixed to said circular sheet in proximity to said open end; a plate, hinged to the front top edge of said rectangular shell; a thimble mounted on said rectangular shell and in open communication therewith; a pipe adapted to be connected with a smoke 90 pipe or chimney flue; a sleeve, having a pair of angular slots therein, detachably connected with said thimble and movably mounted on said pipe; and a damper, mounted on an operating shaft, the ends of which extend through said angular slots, disposed within 95 said pipe.

5. In an equipment of the class described, the combination of a container comprising a shell having a slot in its lower edge, a bottom having an opening therein and an inwardly tapering shell disposed within said shell in proximity to said bottom; a slidable plate disposed on said bottom and extending through said slot; a hood, comprising a sheet, fixed to top of said container, having an opening therein and a shell open below and at one end fixed to said sheet above said opening; a plate hinged to the top edge of open end of said shell; a pan fixed to said sheet in proximity to said open end; a thimble, mounted on said shell and in open communication therewith; a pipe adapted to be connected with a smoke pipe or chimney flue; a sleeve, having a pair of angular slots therein, detachably connected with said thimble and movably mounted on said pipe; and a damper, mounted on an operating shaft, the ends of which extend through said angular slots, disposed within 110 said pipe.

6. In an equipment of the class described, the combination of a hood, comprising a sheet having an opening therein, and a shell open below and at one end, fixed to said

sheet above said opening; a plate, having a slot therein, hinged to the top edge of open end of said shell; a pan fixed to said sheet in proximity to said open end; a thimble, mounted on said shell and in open communication therewith; a damper, mounted on an operating shaft, disposed within said

thimble; and a pipe, having a pair of angular slots through which the ends of said operating shaft project, mounted loosely on 10 said thimble and adapted to be connected with a smoke pipe or a chimney.

OLIVER S. BOWMAN.
